CLAIM

The ornamental design for a humidifier, as shown and described.

DESCRIPTION

FIG. 1 is a front, right, top perspective view of a humidifier, showing our new design;

FIG. 2 is a front elevational view thereof;

FIG. 3 is a rear elevational view thereof;

FIG. 4 is a left side view thereof;

FIG. 5 is a right side view thereof; and,

FIG. 6 is a top plan view thereof.

The dashed broken lines in the figures are for the purposes of illustrating portions of the humidifier and form no part of the claimed design.
